Franklin H. Longfellow

Attorney,

UNITED STATES PATENT OFFICE.

HIRAM CONE, OF ONEIDA, NEW YORK.

WOOD-WORKING CLAMP.

SPECIFICATION forming part of Letters Patent No. 424,960, dated April 8, 1890.

Application filed October 31, 1889. Serial No. 328,747. (No model.)

To all whom it may concern:

Be it known that I, HIRAM CONE, a citizen of the United States, residing at Oneida, in the county of Madison and State of New York, have invented certain new and useful Improvements in Wood-Working Clamps; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to certain new and useful improvements in adjustable wood-working clamps; and it has for its object to simplify and cheapen the construction and to render more efficient, durable, and serviceable in operation this class of devices.

To these ends and to such others as the invention may pertain the same consists in the peculiar combinations and in the novel construction, arrangement, and adaptation of parts, all as more fully hereinafter described, shown in the accompanying drawings, and then specifically defined in the appended claim.

The invention is clearly illustrated in the accompanying drawings, which, with the letters of reference marked thereon, form a part of this specification, like letters of reference indicating like parts throughout both views, and in which drawings—

Figure 1 is a perspective view of a clamping device constructed in accordance with my invention, the adjustable section being shown as locked. Fig. 2 is a central vertical longitudinal section of the same, in which the position occupied by the locking-key when the parts are unlocked is indicated by dotted lines.

Reference now being had to the details of the drawings by letter, A and B, respectively, represent the two sections of the device. The section A carries at its free end the vertical post or upright C, through which is passed the vise-screw D, provided at its outer end with an operating lever or handle E, and having a clamping-block F connected with its

opposite end by means of a universal joint, 50 as shown.

The upper face of the horizontal strip A², which forms the body of the movable section A, is provided with a series of serrations or notches a a, which notches are adapted to engage the corresponding notches b b, formed upon the under face of the inner end of the section B, when thrown into engagement with said notches, as hereinafter specified.

J is an open-ended casing secured to and depending from the inner end of the section B, said casing being of a size sufficient to permit the strip A² to be passed loosely through it and moved freely therein in a longitudinal direction. The outer end of the section B is provided with an upright or standard K, which serves as one of the jaws of the clamp.

The key L is a substantially wedge-shaped piece of either wood or metal, which is cut 70 away upon its under side, so as to form the space M adjacent to the smaller end of the key, the length of this cut-away portion corresponding with the width of the casing J.

The operation of the clamp will be readily 75 understood. When it is desired to change the point of adjustment of the parts, the key L is moved so as to occupy the portion shown in dotted lines in Fig. 2 of the drawings. The sections having been unlocked, may be 80 moved to the desired point of adjustment, when by forcing the key securely into place within the casing, the notches a are thrown into engagement with the notches b upon the section B, and the sections securely locked together.

Having thus described my invention, what I claim to be new, and desire to secure by Letters Patent, is—

As an improved article of manufacture, the 90 herein-described clamping device, the same comprising, in combination, a movable section having a horizontal body portion notched upon its upper face, provided at its free end with an upright having a vise-screw passed 95 therethrough, a section B, carrying at its outer end an upright K and having notches b formed upon its under face adjacent to its

free end, the casing J, depending from the inner end of the section B and adapted to loosely receive the strip A², and the substantially wedge-shaped key L, adapted for use 5 in locking the sections in their adjusted positions, substantially as and for the purpose described.

In testimony whereof I affix my signature in presence of two witnesses.

HIRAM CONE.
